UNITED STATES PATENT OFFICE

WILLIAM HUGER HARDIE, OF NEW YORK, N. Y., ASSIGNOR TO FOSTER WHEELER CORPORATION, OF NEW YORK, N. Y., A CORPORATION OF NEW YORK

STEAM GENERATOR

Application filed February 26, 1931. Serial No. 518,361.

My invention relates to steam generators and more particularly my invention consists in a novel and improved superheater in conjunction with a steam boiler.

5 Among the objects of my invention are: To provide an improved superheater utilizing both convection and radiant heat, to provide a superheater which has a large heat transfer surface, to provide a superheater which is not 10 subject to bending stresses and which is free to expand and contract, to provide a superheater in which the tendency of the superheater tubes to bend and sag is minimized, and to provide a superheater which is supported in an improved manner.

While I have devised this superheater for use in connection with a specific type of boiler, and it has certain specific relationships with and advantages in connection with such type 20 of boiler, it will be understood that the invention may be applied to superheaters used in combination with boilers of other types than that hereinafter disclosed.

25 My improved superheater and its relation to the boiler are described in the following specification, which is to be considered in connection with the accompanying drawings, of which:

Fig. 1 is a sectional elevational view of a 30 steam generator embodying the invention, which view is taken on the line 1—1 of Figs. 2 and 3;

Fig. 2 is a sectional view taken on the line 2—2 of Fig. 1;

Fig. 3 is a sectional view taken on the line 35 3—3 of Fig. 1; and

Fig. 4 is a sectional view taken on the line 4—4 of Fig. 1.

40 The steam generator includes front and rear walls 10 and 11, respectively, side walls 12, and a roof structure 13 enclosing a furnace chamber 14 and a boiler space 15. Suitable means are provided as at 16 to cause combustion to take place in the furnace chamber 14. The boiler space 15 is that portion of the total space enclosed by the walls which contains the boiler. The boiler is designated generally by reference character 17.

50 The particular boiler illustrated includes a

lower horizontal drum 18 and three upper steam and water drums 19, 20, and 21.

Three groups or banks of vertically inclined tubes are connected to drum 18. The forward or radiant bank 22 is adjacent the furnace or combustion chamber and is positioned to receive radiant heat. This bank is connected to drum 19. A second bank of tubes 23, which is a convection bank, is also connected between drum 18 and drum 19. Between these banks is a space 24, which may be termed a superheater space. A bank of tubes 25 connects drum 18 with drum 21. This is a rear bank of tubes with respect to the furnace chamber. Steam connections 26 connect drums 19 and 20. Steam connections 27 connect drums 20 and 21. Water connections 28 connect drums 20 and 21.

55 A baffle 29 extends from the drum 18 along the back of the bank of tubes 22 for some distance, thence transversely to the forward side of bank 23 and upwardly along the forward side of bank 23, leaving a passage for products of combustion between the upper end of this baffle and the drum 19. A 60 baffle 30 extends downwardly from drum 20 and along the rear side of bank 23, thence transversely to the forward side of bank 25 and upwardly along the forward side of bank 25 to the drum 21. A passage is formed for 65 products of combustion between the lower end of this baffle and drum 18. A baffle 31 extends upwardly from the rear wall 11 along the rear side of bank 25 and laterally to the outlet flue 32. A passage 33 is provided at the rear of the top of the bank 25. An economizer 34 is situated in the flue 32. The path of the products of combustion is generally upward along bank 22, downward along bank 23, upward along bank 25, and 70 downward through flue 32.

75 Within drum 18 are plates 35 forming a chamber 36. The rearmost tubes of bank 25 are connected to this chamber and to a header 37, constituting a feed water inlet header. 80 Two other rows of tubes are connected to chamber 36. Feed water passes from header 37 downwardly through the rearmost tubes of bank 25 and thence upwardly through the next two rows and into drum 21. Water is 85

present in drum 18 and all the tubes of the various banks, and in the three drums 19, 20, and 21 to a height substantially as shown in Fig. 1. Steam is withdrawn from the upper 5 part of drum 20 through conduit 38.

Conduit 38 is connected to upper superheater header 40. This header is arranged horizontally and between drums 19 and 20. A lower superheater header 41 is supported 10 in the baffle 29. Between these two headers extend the superheater tubes 42.

Beginning at the upper superheater header 40, it will be seen that the superheater tubes extend downwardly and forwardly in the 15 lanes of the water tube bank 23, thence forwardly into lanes between tubes of the forward bank of water tubes 22, thence rearwardly into the superheater space 24, thence forwardly into the lanes between the tubes 20 of bank 22 and again rearwardly to connect with the lower superheater header 41. The tubes are supported at 43 by the baffle 29. It will be seen that the forward bends 44 and 25 46 of the superheater tubes extend toward the furnace chamber so as to be exposed to radiant heat from the fire in the combustion chamber. The more rearward portions of the superheater tubes are heated by convection heat. The configuration of the tubes 30 provides a large tube surface for a given distance between headers. The intermediate support of the tubes maintains them in position and prevents sagging. It will be seen that the configuration of the tubes permits 35 freedom of expansion and contraction.

Header 40 is divided by means of a partition 47. As shown in Fig. 3, the steam to be superheated passes into the left-hand side of header 40, thence through the left-hand 40 superheater tubes, thence through the header 41, upwardly through the right-hand superheater tubes and out through the right-hand connection, all as shown in Fig. 3.

It will be understood that variations may 45 be made within the scope of the invention.

What I claim is:

1. A steam generator comprising walls enclosing a furnace chamber and a boiler space, a boiler in the boiler space comprising an 50 upper drum, a lower drum, a bank of vertically inclined tubes connecting the lower and upper drums and arranged to receive radiant heat, and a superheater comprising headers behind the bank and tubes connecting the 55 headers, an intermediate support for the tubes behind the bank and said tubes having bends between the support and the headers extending forwardly toward the furnace chamber in lanes in said bank.

2. A steam generator comprising walls enclosing a furnace chamber and a boiler space, a boiler in the boiler space comprising an upper drum, a lower drum, a forward bank 60 of vertically inclined tubes connecting the lower and upper drums and arranged to re-

ceive radiant heat, a convection bank of vertically inclined tubes connecting the lower and upper drums, a baffle between said banks and a superheater comprising headers behind the forward bank and tubes connecting the 70 headers having intermediate portions thereof supported on said baffle and having bends extending forwardly toward the furnace chamber in lanes in said forward bank.

3. A steam generator comprising walls enclosing a furnace chamber and a boiler space, a boiler in the boiler space comprising an upper drum, a lower drum, a forward bank of vertically inclined tubes connecting the lower and upper drums, a baffle between said banks and a superheater comprising an upper header and a lower header behind the forward bank and tubes connecting the headers having intermediate portions thereof supported on said baffle and having bends extending forwardly toward the furnace chamber in lanes 80 in said forward bank, said baffle having a portion thereof adjacent the rear side of the forward bank and a portion thereof adjacent the forward side of the convection bank and a transverse portion connecting the aforesaid portions, said lower header being inserted in 85 said transverse portion.

4. A steam generator comprising walls enclosing a furnace chamber and a boiler space, a boiler in the boiler space comprising an upper drum, a lower drum, a forward bank of vertically inclined tubes connecting the lower and upper drums and arranged to receive 90 radiant heat, a convection bank of vertically inclined tubes connecting the lower and upper drums, a baffle between said banks and a superheater comprising headers behind the forward bank and zigzag tubes connecting the headers having intermediate portions 95 thereof supported on said baffle.

5. A steam generator comprising walls enclosing a furnace chamber and a boiler space, a boiler in the boiler space comprising an upper drum, a lower drum, a forward bank of vertically inclined tubes connecting the lower and upper drums and arranged to receive 100 radiant heat, a convection bank of vertically inclined tubes connecting the lower and upper drums, a baffle between said banks and a superheater comprising headers behind the forward bank and tubes connecting the headers having intermediate portions thereof supported on said baffle and having bends extending forwardly toward the furnace chamber in lanes in said forward bank.

6. A steam generator comprising walls enclosing a furnace chamber and a boiler space, a boiler in the boiler space comprising an upper drum, a lower drum, a forward bank of vertically inclined tubes connecting the lower and upper drums and arranged to 110

receive radiant heat, a convection bank of vertically inclined tubes connecting the lower and upper drums, a baffle between said banks and a superheater comprising an upper header and a lower header behind the forward bank and tubes connecting the headers having intermediate portions thereof supported adjacent said baffle and having bends extending forwardly toward the furnace chamber

5 in lanes in said forward bank, said baffle having a portion thereof adjacent the rear side of the forward bank and a portion thereof adjacent the forward side of the convection bank and a transverse portion connecting the

10 aforesaid portions, said lower header being inserted in said transverse portion.

7. A steam generator comprising walls enclosing a furnace chamber and a boiler space, a boiler in the boiler space comprising an

20 upper drum, a lower drum, a forward bank of vertically inclined tubes connecting the lower and upper drums and arranged to receive radiant heat, a convection bank of vertically inclined tubes connecting the lower

25 and upper drums, a baffle between said banks and a superheater comprising headers behind the forward bank and zigzag tubes connecting the headers having intermediate portions thereof supported adjacent said baffle.

30 In testimony whereof I have affixed my signature.

WILLIAM HUGER HARDIE.
